Specification of Letters Patent.

Patented Feb. 1, 1921.

Application filed January 15, 1919. Serial No. 271,202.

To all whom it may concern:

Be it known that we, ANDREW K. BRUMBAUGH, of Ardmore, in the county of Montgomery and State of Pennsylvania, JAMES W. REDDING, of Philadelphia, in the county of Philadelphia and State of Pennsylvania, and LOUIS S. CLARKE, of Haverford, in the county of Montgomery and State of Pennsylvania, have jointly invented certain new and useful Improvements in Explosive Projectiles, whereof the following is a specification, reference being had to the accompanying drawings.

The invention relates to explosive projectiles of the class generally known as "bombs," and more especially to that type of such projectiles intended to be dropped from aircraft.

It is requisite that a weapon of the class referred to be universally applicable in attacks both upon land and at sea, thereby presenting different conditions under which detonation is to be controlled in order to be most effective. In certain instances, delayed detonation is most desirable for example, in attacks at sea upon submarines or mine fields which are at a considerable distance below the surface level, or again in land attacks upon buildings, etc., where the best results are attained when the explosion occurs after a substantial penetration into the interior. In other instances, instantaneous detonation is most desirable as in attacks upon surface vessels afloat, or in general land bombing.

With these ends in view, we have invented a projectile with a detonating mechanism which is automatically and selectively operable for either delayed or instantaneous explosion, depending entirely upon the physical nature of the material or substance encountered.

The invention also comprehends a detonating mechanism for explosive projectiles, which mechanism is normally maintained in "safe" or unarmed position, but which, upon release, is capable of self setting in a comparatively short time interval, in readiness for detonation under either of the conditions above set forth. The interval is however of sufficient duration to insure that the projectile has reached a safe distance from the aeroplane before the detonating mechanism is set, thereby affording protec-

tion against premature or accidental explosion.

The invention further comprehends certain other adjunctive controlling features which will be best understood by reference to the drawings in which,

Figure I, is a longitudinal section through the forward end of an explosive projectile conveniently embodying our invention. In this illustration the various parts of the detonating mechanism are shown in their normal or "safe" relation.

Fig. II, is a perspective view of the firing plunger, a portion of the upper end having been removed to show the relative positions of the inner ends of the delay and impact firing pins.

Fig. III, is a view similar to Fig. II, but observed from another angle and showing the relative positions of the forward ends of the delay and impact firing pins.

Fig. IV, is a detail section on the line IV-IV in Fig. I.

Fig. V, is a view similar to Fig. I, in a plane at 45 degrees from the latter, and showing the relative positions occupied by the various elements of the detonating mechanism when, "armed," in readiness for detonation.

Fig. VI, is a perspective view of the annulus against which the firing pins react in effecting the detonation of the projectile.

Figs. VII and VIII, are detail sectional views taken respectively on the lines VII-VII and VIII-VIII of Fig. V.

The projectile to which our invention is applied in the illustrations, is of standard form, consisting of an elongated tubular body portion 1, inclosing a chamber 2, in which the main explosive charge is stored. This body portion is supplemented by a tapered nose piece 3, internally threaded at the smaller end as indicated at 4, for engagement with the ferrule 5, of tube 6, which incloses the movable parts of the detonating mechanism. Said tube occupies a coaxial position with respect to the body portion 1, and terminates at its inner end, well within the interior of the chamber 2, it being further supported about midway of its length in a central aperture 7, of a cover plate 8, which is screwed fast to the top of the nose piece and serves as a hermetical closure for the bottom of chamber 2. The joints be-

between the several casing parts thus far described are rendered watertight by interposed gaskets 9-9, as clearly shown in Figs. 1 and 7.

5 The ferrule 5, is in turn internally threaded as indicated at 10, to receive a bearing annulus 11, for the driving shaft 12, to the lower end of which is secured a propeller 13. Within the confines of the bearing 11, said shaft is provided with a series of peripheral grooves 15, which are packed with grease or other suitable packing to prevent the ingress of water. For the same reason, the end of the bearing 11, is seated within a recess 16, formed in the hub of the propeller. Longitudinal displacement of the shaft in the bearing is prevented by the co-operation of a fixed collar 17. The inner threaded end 18, of the shaft is normally received, as shown in Fig. 1, within the axial bore 21, of a plunger 20, having at its lower end an inserted nut 22, adapted for threaded engagement. Plunger 20, is restricted to longitudinal motion in the tube 6, by the engagement of the depressions 23-23, and 25-25, which serve as keys in co-operation with slideways 26-26, in the said plunger.

Plunger 20, carries the firing pins 30-30, and 31-31, the former of which we will term, for convenience, the delay firing pins, and the latter, the impact firing pins, the functional adjectives being employed for reasons which will become apparent from further description. The delay firing pins 30-30 are ordinarily held in fixed relation to the plunger by cross pins 32-32, of lead or other comparatively soft metal, and the impact firing pins 31-31, by cross pins 33, of similar metal of somewhat larger cross section. From Fig. 11, it will be noted that the protruding lower ends of the delay firing pins 30-30, are larger than those of the impact pins 31-31, and engage with the proximate faces of the coaxial blocks 35-35, carried by a reactive member in the form of an annular nut 36, also adapted for threaded engagement with the screw shank of the propeller shaft. The blocks 35, are ordinarily retained in position in the member 36, by cross pins 37, preferably of brass which under certain conditions yield to shearing in a manner to be hereinafter explained. Normally, the member 36, bears a fixed relation with respect to the plunger 20, in so far as longitudinal movement is concerned, independent rotation thereof being prevented through the instrumentality of a guide post 38, fixed in the lower end of the plunger and projecting within a receiving aperture 39, in the said member.

To the upper end of the plunger is attached a blasting cap 50, containing a suitable explosive charge and retained in place by an insertion nut 51. Directly beneath the seat for the cap 50, is located a control

cavity 52, which is common to a series of radiating channels 53-53, and 55-55, which communicate respectively with vertical ducts 54-54, and 56-56, co-axially aligned with the firing pins 30-30 and 31-31. Seated within the mouths of the ducts 54, and 56, are a series of primers 60, the plunger 20, being provided at this region with an annular groove or channel 62, to facilitate ready access in charging.

The channels 53-53, are packed with a slow burning powder, while their communicating ducts 54-54, aligned with the delay firing pins are preferably packed with instantaneous burning glazed black powder 80 to insure proper ignition of the former. The time fuse thus constituted is serviceable for delayed detonation in a manner to be more fully described later. In order to facilitate the proper consumption of the slow burning fuse powder, we have provided vent holes 57-57, (Figs. I, VI, and VII) through which the combustion gases are permitted to escape. These vents communicate with grooves 58-58, preferably disposed at an angle as best shown in Fig. III, and which in turn lead to the annular channel 62, of the plunger.

The other channels 55-55, and communicating ducts 56-56, aligned with the impact plungers 31-31, and also the common central cavity 52, are packed with glazed black powder for instantaneous consumption, which thus constitutes a quick acting fuse.

Within the upper end of the guide tube 100 6, is inserted a cylindrical hermetically sealed container 65, for a suitable charge of a booster explosive. The normal position of this container, as illustrated in Fig. I, is determined by the interned shoulder 105 formed by the integral key depressions 23, of the tube. A spring 66, interposed between the cap 67, of the tube and the container 65, serves to hold the latter yieldingly in engagement with its stops 21. The bottom 68, of the container is formed with a well 69, for the reception of the blasting cap 50, when the parts are in the armed position illustrated in Fig. V.

A retarding disk 70, is secured at the lower end of the nose piece 3, behind a shoulder 71, on the ferrule 5. Said disk is functionally effective in retarding the progress of the projectile in water.

In order to guard against accidents the detonating mechanism is ordinarily locked in the "safe" position illustrated in Fig. I, by a device which is about to be described. This comprises an arm 75, which is secured to the protruding portion of the bearing annulus 11, by means of a clamp screw 76. At its outer end the arm 75, is formed with a bifurcated head 77, within which is received a stop finger 78, having its free end rounded as at 79, in opposition to the curved backs 130

of the propeller blades. Finger 78, is suspended from a pivot pin 80, and is adapted normally to be fixed against movement by a cotter pin 81, which is provided with a suitable handle 83, which is attached to an appropriate controlling mechanism (not shown) operable at the will of the operator.

By this means, the aviator is enabled to release the projectile either with or without the cotter pin. Such a provision is important since it is sometimes necessary in emergencies to drop bombs upon friendly territory in order to lighten air craft, of the dirigible balloon type to permit maneuvering. Likewise in hydro-aeroplane operation it is sometimes necessary to discard the bombs in reducing weight to permit ascension under reduced engine power. These conditions are of course, abnormal, but when thus released, the projectiles are safe against explosion by virtue of the retained cotter pin by which the propeller locking device is fixed against motion. In normal operation, upon withdrawal of the cotter pin 81, finger 78, will readily yield to the rotation of the propeller, the curved edge 79, sliding freely over the rounded backs of the propeller blades. The swinging of the finger about its pivot is restricted to one direction only, a stop 82, being provided for this purpose.

The action of the detonating mechanism may be briefly described as follows:

In releasing the projectile from the air craft, the cotter pin 81, of the propeller lock is automatically withdrawn by virtue of its fixed attachment as already described. Consequent upon its release, the projectile immediately assumes the vertical position illustrated in Fig. I, of the drawing, through the action of a suitable guide tail (not shown) such as is ordinarily provided for this purpose. The propeller having been set free rotates in a counter clock wise direction under the propulsion afforded by the action of the air during descent. In Fig. I, it will be noted that both the anvil 86, and the plunger 20, are in threaded engagement with the propeller shaft and as a result, will be simultaneously moved vertically in the tube 6, through the motion of the propeller. This action continues until the reaction member 36, encounters the abrupt shoulders formed at the lower end of the tube depressions 23-25, whereupon the parts come to rest in the position illustrated in Fig. V. In actual practice the time interval required to effect this is four and one half seconds, the various elements of the detonator being so proportioned as to predetermine the above. During the upward movement of the plunger, the blasting cap 50, enters its receiving well 69, in the bottom of the booster container 65, and the latter yields to being shifted vertically under the resiliency of its retaining spring 60. The parts as

thus represented in Fig. V, are in the armed position and ready to effect detonation. It is important to note that the final portion of the progression of the plunger is accomplished by virtue of the threaded engagement of the propeller shaft with the member 36, alone, so that in the "armed" position, the plunger is freed for independent longitudinal motion in the guide tube 6. Such independent motion is however prevented during flight since the lower ends of the delay firing pins 80-80, still serve to space the plunger from the reaction member, the cross pins by which the said pins are secured being of sufficient strength to prevent dislodgment.

Detonation of the projectile is automatically and selectively accomplished in two ways depending upon the physical nature of the object or medium encountered. We will first describe the delayed action which is as follows:

When the progress of the projectile is suddenly retarded, for example, by striking water, the momentum of the plunger overcomes the resistance offered by the lead cross pins 82-82, by which the delay firing pins 80, are retained. These pins are thus sheared by the independent movement of the plunger with respect to the firing pins 30, the lower ends of which react against the member 36, in a manner already noted. As a consequence of the plunger movement, the primers 60, are brought into forcible contact with the respective delay firing pins 80, and discharged, thereby igniting the fuse formed by the slow burning powder in the channels 53, (consumed in one and four fifths seconds) which in turn causes the explosion of the booster charge and the main charge in the chamber 2, through the setting off of the blasting cap 50. By reason of the time required for the consumption of the slow burning fuse powder, the projectile travels a considerable distance below the surface level of the water before detonation takes place. This feature is of importance in connection with attacks upon submarines, mine fields, etc. Delayed detonation is also advantageous in attacking buildings so that the projectile may penetrate well into the interior before explosion occurs.

The other condition under which detonation takes place is by direct impact with some solid substance having sufficient reactive capacity to cause the breaking down of all the temporary retaining devices employed in connection with both sets of firing pins. This action may be briefly described as follows:

The retaining pins 82, of the delay firing pins 80, are first broken down by the reaction with member 36, as in the previous instance, by reason of the greater protrusion of the lower ends of the latter over those of the impact firing pins. Simultaneously with

this action, the retaining pins 37, for the insert blocks 35, of the member 36, also yield to the strain with the result that the delay pins 30—30, are projected through the isolated openings in the member. These intermediate barriers having been overcome, the further movement of the plunger causes the shearing of the retaining pins 33, by virtue of the succeeding reaction of the lower ends 10 of the impact firing pins 31, with the member 36. The interposed fuse of the glazed black powder in the channels 55, thereby causes the instantaneous discharge of the blasting cap 50, and the sequential explosions as before.

In either method of detonation, it is to be noted that the plunger becomes an independently movable element, relative to the reaction member 36, and the booster cartridge simply follows the movement of the plunger by virtue of its own inertia and as under the assistance of its retaining spring 66, so that the proper firing relation between the blasting cap and the booster charge is at 25 all times maintained. Selection between the two methods is automatically determined through the different resistive capacities of the temporary retaining elements, and it is of course to be understood that such capacity may be varied indefinitely by proper proportioning of the parts so that detonation may be effected under any predetermined conditions. It is also obvious that the time period required for delayed detonation may be likewise varied by either increasing or decreasing the bulk of the slow burning fuse.

Having thus described our invention, we claim:

1. Detonating mechanism for an explosive projectile comprising time and instantaneous fuses; inertia-actuated means for firing said fuses independently of one another; and means for selectively controlling the action of said means, so as to fire the projectile by one or the other of said fuses, according to the resistance to progress of the projectile offered by the medium encountered by it.

2. Detonating mechanism for an explosive projectile comprising a plurality of fuses; a movable inertia element; and separate means controlled by the inertia action of said element for firing said fuses selectively and independently, according to the resistance to progress of the projectile offered by the medium encountered by it.

3. Detonating mechanism for an explosive projectile comprising a time fuse and an instantaneous fuse; an element movable by inertia to fire said fuses; and means for so limiting the inertia-actuated movement of said element as to fire said fuses selectively according to the resistance offered to the progress of the projectile by the substance encountered.

4. Detonating mechanism for an explosive projectile comprising a plurality of fuses; an inertia element movable to fire the projectile by one or other of said fuses selectively, according to the extent of its inertia-actuated movement; and means ordinarily preventing inertia-actuated movement sufficient to fire the fuse for which the greater extent of such movement is required.

5. Detonating mechanism for an explosive projectile comprising time and instantaneous fuses; inertia-actuated means for firing each of said fuses; and means controlled by the flight of the projectile for initially maintaining said inertia-actuated means inoperative and out of firing relation to the projectile charge, and for eventually shifting the same into firing relation thereto and releasing the same for inertia-actuation.

6. A detonating mechanism for an explosive projectile comprising time and instantaneous fuses; an element movable to fire the projectile by one or other of said fuses selectively, according to the extent of its movement, and responsive to resistance offered to progress of the projectile by the medium encountered by it; and means for limiting the resistance-controlled movement of said element to control its selective action as aforesaid.

7. A detonating mechanism for an explosive projectile comprising a guide tube; and an inertia-actuated plunger slidably therein; a fuse carried by said plunger; a firing pin slidably in and guided by said plunger, and two means normally securing said firing pin to the plunger; and reactive means in the way of movement of said firing pin with the plunger for detaching said pin from said plunger when the plunger is actuated and causing said firing pin to ignite said fuse.

8. A detonating mechanism for an explosive projectile comprising a guide tube; a weighted plunger slidably guided in said tube; a fuse carried by said plunger; a firing pin mounted within the plunger and protruding therefrom; a cross pin for maintaining said firing pin in fixed relation to the plunger; reactive means for supporting the protruding end of the firing pin, so that when the progress of the projectile is suddenly arrested, the momentum of the plunger will cause said cross pin to be sheared and said firing pin to fire the fuse.

9. A detonating mechanism for an explosive projectile comprising a guide tube; a slideable weighted plunger guided within said tube; a time fuse and an instantaneous fuse carried by said plunger; a firing pin associated with each of said fuses; retaining means for normally holding each of said pins in fixed relation to the plunger, said respective retaining means being capable of yielding under stresses of different degrees, whereby the plunger is automatically

cally and selectively released to cause the firing of either the time or instantaneous fuse according to the degree of resistance offered to the progress of the projectile.

5 10. A detonating mechanism for an explosive projectile comprising movable inertia and reactive members; means for normally maintaining said inertia and reactive members in fixed relation and for shifting

10 one of them into operating position and releasing the other, including a member normally engaging said members but shiftable to disengage it from one of them; and means controlled by flight of the projectile for 15 shifting said engaging member as aforesaid.

11. A detonating mechanism comprising a movable member, and a reactive member; a screw normally in threaded engagement with both members to hold the same in fixed

20 relation to prevent accidental detonation; and means for rotating the said screw to release one of said members for relative independent motion upon the release of the projectile.

25 12. A detonating mechanism comprising a movable member, and a reactive member; a screw normally in threaded engagement with both members to hold the same in fixed relation to prevent accidental detonation; 30 and an air operated propeller for rotating said screw to release one of said members for relative independent motion upon the release of the projectile.

13. A detonating mechanism comprising 35 a guide tube; a plunger restricted to longitudinal movement in the said tube; a fuse associated with said plunger; a reactive member co-axially aligned with said plunger and also restricted to longitudinal move-

40 ment in the said tube; a screw normally having threaded engagement with both the plunger and the reactive member whereby said elements are ordinarily held from relative independent motion to prevent accident- 45

50 al explosion; and an air operated propeller for rotating said screw whereby the said plunger is ultimately released for independent motion with respect to said reactive element, in readiness to fire said fuse.

55 14. A detonating mechanism for an explosive projectile comprising an inertia-actuated longitudinally movable plunger; a booster cartridge interposed in the path of movement of said plunger; a screw nor-

60 mally in threaded engagement with said plunger to hold the same spaced from the booster cartridge; and means operated by the flight of the projectile for rotating said screw to advance said plunger into firing

65 relation to the booster cartridge.

15. A detonating mechanism for an ex-

plosive projectile comprising a guide tube extending into proximity to the main explosive charge; a plunger restricted to longitudinal movement in the said tube; a booster cartridge interposed in the tube between said plunger and the main explosive charge; stops for normally determining the position of the cartridge in the tube; a retaining spring for yieldingly maintaining 70 said cartridge in engagement with its stops; a screw for normally engaging said plunger to hold the same in spaced relation with respect to the cartridge; and an air operated propeller for automatically advancing the 75 plunger into engagement with the cartridge in opposition to the retaining spring.

16. A detonating mechanism for an explosive projectile comprising a movable member and a reactive member; a screw normally engaging both members to hold the same in fixed relation to prevent accidental detonation; an air operated propeller for automatically rotating said screw to release 80 one of said members for relative independent motion upon the release of the projectile; and means for normally locking said propeller against rotation, said locking means including a pivoted finger adapted to project between the blades of the propeller 85 and having a curved deflecting edge adapted to coöperate with the propeller blades to permit the operation of the propeller when released; and a detachable securing means for normally holding said locking 90 finger in fixed position.

17. An explosive projectile comprising a body adapted to contain the main explosive charge; a supplemental nose piece attached to said body, with its interior separated 100 from that of said body; a guide tube removably secured in the forward end of said nose piece and extending therethrough into the interior of said body; a booster charge in the inner end of said tube, within said body; 105 a detonating device guided in said tube; and means controlled by the flight of the projectile for shifting said detonating device from a position in said nose piece into firing proximity to said booster charge; said 110 last-mentioned means being associated and removable with said tube, said booster charge, and said detonating device.

In testimony whereof, we have hereunto signed our names at Philadelphia, Pennsylvania, this second day of January, 1919.
